UNITED STATES PATENT OFFICE.

HUGH M. ROCKWELL, OF BRISTOL, CONNECTICUT, ASSIGNOR TO MARLIN-ROCKWELL CORPORATION, OF NEW YORK, N. Y., A CORPORATION OF NEW YORK.

WHEEL-DRESSING DEVICE.

Application filed May 29, 1920, Serial No. 385,223. Renewed June 13, 1924.

To all whom it may concern:

Be it known that I, HUGH M. ROCKWELL, a citizen of the United States, and a resident of Bristol, in the county of Hartford and 5 State of Connecticut, have invented certain new and useful Improvements in Wheel-Dressing Devices, of which the following is a specification.

This invention relates to a device for 10 dressing the cutting surface of a grinding wheel.

In the grinding of the raceways or ball grooves for antifriction bearings, it is generally customary to shape the cutting surface 15 of the grinding wheel to conform to the curvature of the ball groove to be ground thereby. It is the object of this invention to provide a device for dressing the cutting surface of a grinding wheel to give to it the 20 desired curvature.

A further object of this invention is the provision of a device of this character which also serves as a shield for the grinding wheel.

To accomplish this object, I provide a feed member on the wheel-carrying head arranged for movement in a direction at right angles to the axis of rotation of the wheel spindle. On said feed member is fastened a 25 bracket having curved arms between the ends of which is pivotally mounted a curved frame. A pin or the like carrying a diamond in one end is adjustably supported on the frame and is arranged to traverse the cutting 30 surface of the wheel when the frame is oscillated. To use the device the diamond carrier is adjusted to so locate the diamond that, when the frame is oscillated, it will 35 traverse a curved path of the desired radius 40 to dress the cutting surface of the wheel to the proper curvature. By means of the feed member the bracket may be moved to bring the diamond into contact with the surface to be dressed, in which position of the device 45 the wheel is partially enveloped, thereby thus providing a shield therefor.

In the accompanying drawings wherein is disclosed an embodiment of the invention,

Fig. 1 is an elevation, partly in section, of 50 the device as applied to a grinding machine;

Fig. 2 is a plan view;

Fig. 3 is a section on line 3—3 of Fig. 4;

Fig. 4 is a section on line 4—4 of Fig. 2;

Fig. 5 is an enlarged detail elevation, 55 partly in section, of the device;

Fig. 6 is a section on line 6—6 of Fig. 5.

The head 1 of a grinding machine has journalled therein a spindle upon which is mounted the grinding wheel 2. A projection 3 extends from the head at right angles to the axis of rotation of the spindle. A bore 4 leads from the end of the projection 3 through the base of the head 1 to a recess 5 in the other side of the head. The projection 3 is cut away to form the slot 6 and 60 also to form the aperture 7. Mounted in the bore 4 is the hollow interiorly-threaded slide 8, the arm 9 of which is seated in the slot 6. The surface of the slide is grooved at 10 and arranged in the aperture 7 to fit in the 65 groove 10 is a key 11, which key is held in place by the plate 12 bolted to the projection 3, in which plate is mounted the set screw 13, having a shank 14 adapted to enter the 70 socket 15 in the key. Interposed between 75 the key and the head of the set screw and surrounding the shank 14 is the leather plug 16. Pressure is exerted on the key through the plug 16 to exert friction on the slide 8 to prevent free reciprocatory movement 80 thereof. In the recess 5 is the plate 17 which is held in place by the bolts 18 passing through the curved slots 19 in the plate. Extending through the plate is an aperture 85 20, concentric with which is the collar 21 on 85 the outer face of the plate, which collar is cut away at 22, one end of the collar being shaped to provide a cam surface 23 and the other end presenting a radial shoulder 24. A feed screw 25 has its reduced end 26 90 journalled in the aperture 20 of the plate 17 and the threaded portion thereof operatively associated with the slide 8. Within the collar 21 and keyed to the portion 26 of the feed screw 25 is the ratchet wheel 27. 95 The lever 28 is rotatably mounted on the collar 21 and is provided with a ratchet 29 which is arranged to pass through the cut-out 22 and engage the teeth of the ratchet wheel when the lever is in the position 100 shown in Fig. 3. A leather washer 30 is interposed between the ratchet wheel and the plate 17 and the steel washer 31 is held against the ratchet wheel and lever 28 by the nut 32. A stop 33 limits the throw of 105 the lever 28.

A movement of the lever 28 in a clockwise direction will cause a partial rotation of the feed screw, due to the engagement of the ratchet with a tooth of the ratchet wheel. 5 The friction exerted by the leather washer 30 prevents backward rotation of the ratchet wheel when the lever is returned to position, and the friction exerted by the key 11 on the slide 8 serves to prevent unintentional 10 movement of the slide. To return the slide to its original position when a new wheel is put on, the lever 28 is moved in a counter-clockwise direction to the position shown in Figs. 1, 2 and 4, the ratchet riding up the 15 cam surface 23, thereby being disengaged from the ratchet wheel and allowing counter-clockwise rotation of the feed screw. The plate 17 may be circumferentially adjusted to so place the cut-out portion 22 that 20 a movement of the lever 28 will advance the ratchet wheel one, two, three, or more teeth, as desired.

A bracket 34, having the curved arms 35 and 36 conforming generally to the periphery 25 of the grinding wheel 2 and acting as a shield, is clamped to the arm 9 of the slide 8 and between said arms is rotatably mounted the frame 37. In the lower arm 35 of the bracket is arranged a bearing 38 30 having a socket in its upper end, and the lower end of the frame carries a similar bearing 39, having a socket 40 in its lower face. A ball 41 is seated partly in one socket and partly in the other. On the upper end 35 of the bearing 39 is another socket 42. The upper arm 36 of the bracket carries a bearing 43, having a bell-mounted aperture extending therethrough in which is mounted the shank 44 of the bearing 45 carried by 40 the frame 37. Between the head of the bearing 45 and the bell mouth of the bearing 43 are arranged antifriction balls 46. In the lower face of the bearing 45 is a socket 47. Clamped to the upper portion of the shank 44 extending above the arm 36 of the bracket 34 is the operating lever 48. A pin 49 having at one end the diamond 50, is mounted in an aperture in the frame 37 and is held in any desired position by the contact therewith of the plug 51 against which 50 bears the end of the set screw 52.

In the operation of this device the diamond 50 is set at the proper point to describe the desired arc when the carrier is 55 oscillated. The carrier is then fed into position to engage the diamond with the cutting surface to be dressed by means of the feed screw 25. When in position the carrier is oscillated by means of the lever 48 to move 60 the diamond across the wheel to be dressed.

In order to set the diamond at the desired radius, a gage 53 is used. This gage 65 comprises a substantially cylindrical member having a conical head 54 at one end and an enlarged cylindrical intermediate por-

tion 55. In the other end is yieldingly mounted a plunger 56 having a conical head 57, the outward movement of the plunger being limited in any suitable manner. The conical heads of the gage are inserted in 70 the sockets 42 and 47, bringing the portion 55 into position to be engaged by the diamond 50. The pin 49 is then tapped to bring the diamond into contact with the portion 55, after which the pin is clamped in 75 position and the gage removed.

What I claim is:

1. In a device of the character described, a bracket, bearings in said bracket, one of which has an aperture therethrough and the other of which has a socket, a frame, bearings on said frame, a shank on one of said bearings extending through said aperture, a socket in the other of said bearings, a ball seated in said socket, and a wheel-dressing 85 tool carried by said frame.

2. In a device of the character described, a frame, a wheel-dressing tool carried by the frame, said frame having opposed sockets, and a gage having a portion to be engaged by the dressing tool to properly position said tool and having heads to enter said sockets, one of said heads being reciprocable.

3. A gage for setting a dressing tool in its carrier comprising a cylindrical member having a conical head and an enlarged portion and a pin having a conical head yieldably mounted in said cylindrical member.

4. In a device of the character described, 100 a housing, a slide mounted in said housing, a groove in said slide, a key carried by said housing and contacting with the surface of said groove, resilient means holding said key in contact with the surface of said 105 groove, and means to reciprocate said slide.

5. In a device of the character described, a housing, a slide having a groove therein mounted in said housing, means to reciprocate said slide and friction means comprising 110 a key carried by said housing and engaged with said groove, and resilient means to hold said key in contact with the surface of the groove.

6. In a device of the character described, 115 a housing, a slide having a groove therein mounted in said housing, means to reciprocate said slide, and friction means comprising a recessed key carried by said housing and engaged with said groove, a set screw 120 having a shank adapted to enter the recess in the key, and a resilient sleeve carried by said shank and contacting with said key.

7. In a device of the character described, 125 a feed screw, a ratchet wheel carried by said feed screw, a plate having an aperture through which said feed screw extends, a collar on said plate surrounding said ratchet wheel, said collar being partially cut away, a lever rotatably mounted on said collar, 130

and a ratchet carried by said lever and adapted to extend through said cut-out portion of the collar to engage the teeth of said ratchet wheel.

5 8. In a device of the character described, a feed screw, a ratchet wheel carried by said feed screw, a plate having an aperture through which said feed screw extends, a collar on said plate surrounding said ratchet 10 wheel, said collar being partially cut away, a lever rotatably mounted on said collar, and a ratchet carried by said lever and adapted to extend through said cut-out portion of the collar to engage the teeth of 15 said ratchet wheel, one end of said collar

being shaped to present a cam surface whereby the ratchet may be lifted into inoperative position.

9. In a device of the character described, a feed screw, a ratchet wheel mounted on 20 said feed screw, a collar surrounding said wheel, said collar being partially cut away, a lever rotatably mounted on the collar, a ratchet in said lever adapted to extend through said cut-out portion to engage said 25 ratchet wheel, a stop to limit the movement of said lever, and means whereby said collar may be circumferentially adjusted.

HUGH M. ROCKWELL.
